(57) **CLAIM**

The ornamental design for a beverage bracelet, as shown and described.

DESCRIPTION

FIG. 1 is a front perspective view of a beverage bracelet mounted on a wine bottle;

FIG. 2 is an enlarged front perspective view thereof, mounted on a wine bottle;

FIG. 3 is a front perspective view thereof;

FIG. 4 is a top plan view thereof, the bottom plan view being a mirror image thereof;

FIG. 5 is front elevation view thereof;

FIG. 6 is a rear elevation view thereof;

FIG. 7 is a right side elevation view thereof, the left side elevation view being a mirror image thereof; and,

FIG. 8 is a front perspective view thereof, mounted on a wine glass.

The broken lines shown in the drawings depict a wine bottle and a wine glass that forms no part of the claimed design.

1 Claim, 5 Drawing Sheets
